UNITED STATES PATENT OFFICE.

JOHN W. BURD, JR., OF ST. LOUIS, MISSOURI.

SEAL-LOCK.

SPECIFICATION forming part of Letters Patent No. 295,976, dated April 1, 1884.

Application filed July 30, 1883. (No model.)

To all whom it may concern:

Be it known that I, JOHN W. BURD, Jr., a citizen of the United States, residing at the city of St. Louis, State of Missouri, have invented certain new and useful Improvements 5 in Seal-Locks, of which the following is a specification.

The objects of my improvement are to provide a simple, cheap, and durable seal-lock 10 for use upon railway freight-cars, and to increase the difficulty of unauthorized parties gaining access through the lock without destroying or defacing the seal-card used, so that it can be readily noticed by the parties in 15 charge; and my invention consists in certain detail arrangement and construction of parts, as hereinafter more fully set forth, whereby the above-mentioned objects are attained in a very perfect and efficient manner.

20 In the accompanying drawings, Figure 1 is an elevation of my improved seal-lock; Fig. 2, a vertical section, and Fig. 3 a horizontal section.

Referring to the drawings, A represents the 25 main casing of the lock, secured to the door-jamb of the car, and having a horizontal opening through it for the reception of the locking bar or plate B, that is secured to the car-door. This bar B is recessed out to receive a hinged 30 locking latch or bar, C, the end of which engages the end shoulder, a, of the casing A to lock the parts together.

c is a spring for forcing the latch-bar C down, and c' is a stop-lug on said bar to limit 35 its downward movement.

D is a lock, of any suitable construction, for locking the latch-bar C in its down position, the purpose being to assist in preventing unauthorized opening of the main lock. The 40 drawings show a sliding lock-bar, d, and holding-spring d', with provision for engagement of the operating-key. Any other form of lock found most suitable or convenient may be employed.

45 The part of the casing A in front of the lock-bar B and lock-latch C has provision for the reception of a plate, E, resting on springs e, so as to be capable of a limited motion back from the front plate, A', of the casing, the 50 purpose being to admit of the easy and ready insertion or removal of the seal-card F between the plates A' E. The seal-card is in view through an opening, a', in the front plate, A, this opening being of a smaller size 55 than the seal-card.

e' is an opening through the spring-plate E, in line with the locking-latch C, so as to permit of the introduction of a suitable instrument—such as a pencil—under said latch, to raise it out of engagement with the casing end bar, a, and permit of the lock being opened. It will be seen that to get to the opening e' the card-seal F must be disfigured, and that such disfigurement will show very plainly to the seal-inspector.

65 The seal-cards F are introduced into place from the same end at which the lock-bar B enters, and after the parts are locked its withdrawal is prevented by a projecting lug, b, on lock-bar B, which, for better security, is preferably formed with an overhanging lip, b'.

In the manufacture of my improved lock the front plate, A, will be made separate from the main body of the lock-casing, so as to permit of the insertion of the plate E and other portions of the lock into position, after which the plate A is permanently secured 70 in place by means of rivets or other suitable means.

I am aware that prior to my invention seal-locks have been made with a plate or seal of glass covering an aperture through which access is gained in order to open the lock, and requiring the breakage of the glass before the lock can be opened, such construction being 85 illustrated in Patent No. 154,354, issued August 25, 1874, to John Sweeny. I therefore do not claim such construction, broadly; but

What I do claim, and desire to secure by 90 Letters Patent, is—

1. In a seal-lock, the combination, with the latching mechanism A a B b C, of spring-plate E, having opening e', seal-card F, and front plate, A', all constructed and arranged substantially as herein described, and for the purpose set forth.

2. In a seal-lock, the combination, with a suitable sealing device, of the casing A, abutment-shoulder a, pivoted spring-latch C, stop-lug c', and lock-bar B, recessed out to receive the spring-latch C, as described, and for the purpose set forth.

In testimony whereof, witness my hand this 25th day of April, 1883.

JOHN W. BURD, JR.

In presence of—

L. HALLOCK,
S. S. BISSELL.
